CARL RAUSCH, OF LEIPZIG, GERMANY.

CRIPPLING-MACHINE.

1,214,219.

Specification of Letters Patent. Patented Jan. 30, 1917.

Application filed August 20, 1913. Serial No. 785,661.

To all whom it may concern:

Be it known that I, CARL RAUSCH, a citizen of the German Empire, and residing at Leipzig, in the German Empire, have invented new and useful improvements in Crippling-Machines, of which the following is a full, clear, and accurate specification.

The invention relates to a crippling machine in which the fold of the hide is rolled backward and forward between two parallel plates adapted to be relatively moved. In existing machines of this kind the crippling plates are arranged horizontally, so that the hide to be crippled, in order to be able to follow the movements of the plates, must also be moved horizontally. This has the drawback that the friction between the parts of the hide lying on each other is very great, so that under some circumstances this friction is not overcome by the friction between the crippling plates and hide, so that the crippling plates slide on the hide without being able to roll the fold backward and forward. This drawback is overcome according to the present invention by arranging the crippling plates in a vertical or approximately vertical plane and by moving them in opposite directions, the fold of the hide to be crippled resting on rods on both sides of the plates. By this arrangement the further advantage is obtained that the fold of the hide, during the crippling process, always remains at the same height, so that the manipulation of the hide is much facilitated. In order, in the case of very rough hides, to prevent the parts hanging from the crippling plates being caught together, owing to too great friction, in which case the rolling of the hides is rendered more difficult, a tongue is provided according to the invention which from below rises between the crippling plates and separates the parts of the hide hanging down. Great facility in the attendance of the machine is afforded by the fact that the hide is automatically moved, so that the attendant has only to guide the same. This automatic feed of the hides is obtained according to the invention by reason of the fact that in one direction of motion of a crippling plate the distance between both crippling plates during the period of a stroke or part of a stroke

is increased. Finally a device is used to compensate for the unequal thickness of the hides. One or both crippling plates consist of several parts each of which is resilient. By this arrangement the result is obtained that when the hides have a nonuniform quality, that is, when thin and thick places lie near together, not only the thicker parts, but also the thinner parts are subjected to the pressure of the crippling plates, and, consequently, also are crippled.

On the drawing one construction of the machine is shown in Figure 1 in side elevation and in Fig. 2 in front elevation. Fig. 3 is a side elevation of a machine in which the hides are automatically moved between the crippling plates. Figs. 4 and 5 are a section and elevation respectively of a crippling plate consisting of several independently resilient parts. Fig. 6 is a section showing in detail the means for laterally moving the crippling plates.

On the machine frame *a* there are two slides *b* and *c* carrying the right hand crippling plates *i* and left hand crippling plate *i'* and adapted to move in vertical guides *d* and *e*. The guide *d* of the slide *b* is rigidly connected to the frame *a*, while the guide *e* of the slide *c* is adapted to turn about a pivot *f* provided on the frame *a*. Both slides *b*, *c* are connected by rods *g* to crank disks *h*, by which they are moved up and down. The stroke of the crank disks is equal and these disks are so driven that they always move in opposite directions. The crippling plates *i*, *i'* secured to the slides *b*, *c* are coated with cork or similar rough material on the surfaces facing each other.

To the guide *e* is jointed a rod *k*, which by a lever *l* is so connected with the pedal *m* that on pressing down this pedal the guide *e* approaches the guide *d*, so that the distance between the crippling plates *i*, *i'* is lessened. A spring *n* tends to press back the guide *e*.

When the feed of the hide between the crippling plates has to take place automatically the crippling plate *i* is not fastened to the slide *b* but is carried by bolts *t* which are adapted to move in the slide *b* perpendicular to the surface of the plate *i'*. Springs *u* tend

to press the crippling plate i toward the other crippling plate i^1 . To the bolts t is connected a crank slot v , through which passes a shaft w . On the shaft tappets x are fastened. The shaft is adapted to slide longitudinally, so that the tappet disk secured thereon can be moved in and out of the crank slot v . From the driving gear of the crank shafts h the shaft is so driven that for two, 10 three or more complete revolutions of the crank disks h it turns once as by gear y and belt y^1 . When a tappet disk is in the crank slot v , the tappet in question, moves the crank slot v , together with the bolt t , and the 15 crippling plate connected thereto, horizontally backward and forward, so that the distance between the two crippling plates i, i^1 is increased and decreased. By different lengths of tappets the duration of the increase in the distance of the crippling plates and, hence the period of their separation from each other can be regulated according to desire, while by different angular positions of the tappets the time to increase the 20 distance is adjusted. On the shaft there are at least two tappet disks, one of which removes the crippling plate i from the crippling plate i^1 when the crippling plate i rises, while the other effects the same operation when said crippling plate i falls.

Underneath the two crippling plates i there is a large trough o which takes up the hide to be operated on, so that only a small part of the same hangs free and can follow 35 the movements of the crippling plates. On this trough rest supports p which carry rods q at the top, these rods being arranged on both ends of the tongue between the crippling plates. These rods serve to support 40 the hide r to be operated on, so that said hide can be easily moved and guided. To this trough the tongue s may be attached which projects from below into the space between the plates i , and, by keeping both halves of 45 the hide hanging from the fold apart, facilitates the rolling movement of the hide fold between the crippling plates.

The crippling plate i^1 consists of a number of strips 1 which are connected by springs 2 50 with a plate 3. Bars 4 prevent the strips 1 from falling from the plate 3. Each strip 1 can yield independent of the others, so that, when hides of very irregular thickness are treated, they are pressed together by the 55 crippling plates both at the thinner and thicker parts.

Claims:

1. A crippling machine comprising parallel and substantially upright plates adapted 60 to be moved with the same speed and in opposite directions along a substantially vertical line, for rolling and crippling the hide, and means for supporting the hide during the crippling thereof between the 65 said crippling plates and in a folded con-

dition, each fold being in contact with one of said plates, during the crippling of the hide.

2. A crippling machine comprising parallel and substantially upright plates adapted 70 to be moved in opposite directions along a substantially vertical line, for rolling and crippling the hide, means for supporting the hide during the crippling, and a tongue projecting between the plates and adapted 75 to separate the parts of the hide not between the said plates, during the crippling of the hide.

3. A crippling machine comprising substantially upright plates, means for moving 80 said plates with the same speed in opposite directions for rolling and crippling the hide, a rod on each side of said plates and means to increase the distance of said plates the one from the other for a short time 85 after an even number of strokes of said plates, whereby said hide is automatically fed between said plates.

4. A crippling machine, comprising parallel and substantially upright plates, means 90 for moving said plates with the same speed in opposite directions for rolling and crippling the hide, means for supporting said hides during the crippling, and means to enable one of said plates to be adjusted 95 perpendicular to its direction of movement.

5. A crippling machine, comprising parallel and substantially upright plates, means for moving said plates with the same speed in opposite directions for rolling and crippling the hide, means for supporting said hide during the crippling, and means for periodically moving one of said plates perpendicular to its direction of movement, 100 whereby the said hide is automatically fed 105 between said plates.

6. A crippling machine, comprising parallel and substantially upright plates, means for moving said plates with the same speed in opposite directions for rolling and crippling the hide, means for supporting the hide during the crippling, and a revoluble shaft having tappet disks in different angular positions, said shaft being movable along its axis of revolution, and a crank 110 slot connected with one of said plates and adapted to be actuated by said tappets.

7. A crippling machine, comprising parallel plates having a relative movement in a direction parallel to each other for rolling and crippling the folded hide, means for moving said plates and means intermediate the folds of the hide for maintaining the point at which the hide is folded stationary, with respect to the said plates.

8. A crippling machine, comprising parallel plates having a relative and substantially vertical movement for rolling and crippling the folded hide, means for moving said plates and means intermediate the folds of

the hide for maintaining the point at which the hide is folded stationary, with respect to the said plates.

9. In a crippling machine, parallel plates 5 having a relative and substantially parallel and vertical movement with respect to each other for rolling and crippling the folded hide, and means for moving said plates.

In testimony that I claim the foregoing as my invention, I have signed my name in 10 presence of two subscribing witnesses.

CARL RAUSCH.
